IMPROVEMENT IN SAD-IRON HEATERS.

JOSEPH S. DENNIS, OF CHICAGO, ILLINOIS.

Letters Patent No. 60,150, dated December 4, 1866.

SPECIFICATION.

TO ALL WHOM IT MAY CONCERN:

Be it known that I, JOSEPH S. DENNIS, of Chicago, in the county of Cook, and State of Illinois, have invented a new and useful Improvement in Sad-Irons; and I do hereby declare and make known that the following is a full, clear, and exact description of the same, reference being had to the accompanying drawings, and the letters and figures marked thereon, which form part of this specification.

The nature of my said invention consists in so constructing a sad-iron, that it may be heated as desired by introducing and burning inflammable gas or its equivalent therein, substantially as hereinafter specified.

To enable those skilled in the art to understand how to construct and use my invention, I will proceed to describe the same with particularity, making reference, in so doing, to the aforesaid drawings, in which—

Figure 1 represents a side elevation of my invention.

Figure 2 is a longitudinal vertical central section; and

Figure 3 is a plan or top view of the same.

Similar letters of reference in the several figures indicate the same parts of my invention.

A represents a sad-iron of any suitable configuration, constructed of suitable sheets or plates of metal or cast metal, being hollow, as shown, and divided into two chambers, D and E, by means of a horizontal partition or its equivalent, as hereinafter described. B represents a suitable slide or door, whereby access may be had to the lower chamber, E, when desired, and C is the ordinary handle of the instrument. P represents a flexible tube attached to the sad-iron, as shown, the other end thereof being designed to be suitably secured to an ordinary gas-burner or other device whereby gas may be introduced into said chamber, D; b representing tubes or burners opening downward into the lower chamber, as shown, so that upon igniting the gas thereat, a jet of flame is projected from each down upon the bottom of the sad-iron, thereby thoroughly and sufficiently heating the same; a being apertures to admit air into the chamber to support combustion, and F being a flue to convey off the heated air, and effect a draught. Instead of having the chamber, D, occupy the entire upper part of the sad-iron, the sad-iron may be made of a single chamber, having enclosed within it, in the upper part thereof, an oblong receiver into which the gas may be received, and from which the gas may be distributed by the burners, b, as described and shown. It is designed to have the supply pipe, P, of sufficient length to allow the free sliding or reciprocating movement of the sad-iron, usually adopted in the use of the same. In the forward movement or stroke, the said pipe is extended at length substantially, and in the backward movement, the slack in said pipe is taken up by an elastic cord or band, marked H, which is attached at two points to the tube, leaving a bow or fold in the tube, but which extends in length to permit the extension of said tube when desired in the forward stroke, but which retracts the same as desired when the tension is removed. Instead of attaching the upper end of said elastic strap to the tube, it may be attached to any fixed point, as upon the ceiling, the main point being to take up and remove the slack in the tube, produced as aforesaid, out of the way of the operator. If desired, instead of the downward projecting tubes or burners, b, perforations may be made in the partition to allow jets of gas to project downwards into the combination chamber, with the same results.

Having described the construction and operation of my invention, I will proceed to specify what I claim and desire to secure by Letters Patent:

I claim the chambers D and E, with the inlet and exit tubes, connecting pipes or jets b, and orifices a, constructed and operating substantially as herein described.

J. S. DENNIS.
